ALFRED WINKLER AND MAX DÜNNEBIER, OF NEUWIED-ON-THE-RHINE, GERMANY

APPARATUS FOR FEEDING BLANKS TO ENVELOPE MAKING OR LIKE MACHINES

Application filed September 22, 1930, Serial No. 483,522, and in Germany August 19, 1929.

This invention relates to apparatus for feeding blanks to envelope making or like machines, and has for its principal object to provide improved feeding apparatus for drawing the blanks from a stack and for folding the blanks.

In accomplishing this and other objects of our invention, we have provided improved details of structure, the preferred form of which is illustrated in the accompanying drawings, wherein:

Fig. 1 is a plan view of feeding apparatus embodying our invention.

Fig. 2 is a vertical sectional view on the line 2--2, Fig. 1.

Fig. 3 is a longitudinal sectional view through the indrawing roller particularly illustrating means for regulating effectiveness of the suction area according to widths of the blanks being employed in the machine, and the valve for timing and controlling suction through the roller.

Fig. 4 is a vertical sectional view through the feed rollers illustrating the position of the indrawing roller after the suction element of the roller has moved away from a blank being fed into the forwarding rollers.

Fig. 5 is a sectional view through the valve for timing and controlling effectiveness of the vacuum on the line 5--5, Fig. 3.

Referring more in detail to the drawings:

1 and 2 designate side frames of an envelope making machine, and 3 an inclined plate carried by the side frames for supporting a stack of blanks 4 to be fed into the machine as later described.

Formed in the plate and extending cross-wise of the machine is a rectangular opening 5 through which the blanks are drawn from the stack. The stack of blanks is positioned on the plate in proper relation to the opening by posts 6 which project upwardly from the plate and engage the sides of the blank as shown in Fig. 1.

Rotatably positioned in the opening 5 is a preferably tubular indrawing roller 7 and a solid counter roller 8, the outer peripheries of which are received in concaves 9 and 10 formed in the walls of the opening so that the effective opening in the plate is reduced to a

minimum dimension, thereby relieving tendency of the blanks to sag into the opening and between the respective rollers.

The indrawing roller 7 is rotatably mounted in the frame members 1 and 2, and is driven by a gear 11 meshing with a chain of actuating gears 12 forming a part of the envelope making machine.

The roller 8 is provided with a gear 13 meshing with an aligning gear 13' on the roller 7, and is rotatably supported in yielding contact therewith by arms 14 pivotally mounted on studs 15 carried at the upper ends of brackets 16 which project upwardly from the frame members, as shown in Figs. 1 and 2, and the roller 8 is retained in contact by coil springs 17 connected with pins 18 on the brackets 16 and with pins 19 projecting from the arm 14.

In order to adjust frictional engagement of the roller 8 with the indrawing roller, the brackets 16 are provided with upwardly extending ears 20 for engaging adjustable stop screws 21 threadedly mounted in lugs 22 projecting from the arms 14, the screws 21 being locked in adjusted position by nuts 23 engaging the lugs, as shown in Fig. 2. Also rotatably mounted on the frames 1 and 2 below the rollers 7 and 8 are forwarding rollers 24 and 25 for advancing the blanks into the machine as later described.

The outer peripheries of the rollers 7 and 8 are positioned slightly below the upper surface of the plate 3, so that they may rotate freely beneath the stack of blanks, and in order that the indrawing roller may move the lowermost blank from the stack, we provide for drawing the blank into contact with the roller by vacuum as now described.

The ends of the roller 7 project beyond the side frames to receive at one end a valve 26 for controlling vacuum therein, and at the other end the actuating gear 11 previously described. Formed in the wall of the roller are a plurality of rows of openings designated 28 covering substantially one-quarter of its circumference and through which the vacuum is applied to draw the lowermost blank into engagement with the roller.

The valve 26 includes a bushing 29 sleeved

on the projecting end of the shaft and provided with a slotted port 30 aligning with a complementary port 31 in the roller. Sleeved on the bushing, and preferably fixed thereto by a set screw 32, is a valve housing 33 having a nipple 34 for receiving the end of a conduit 35 connected with a suitable pump (not shown), for drawing a vacuum in the roller. The housing 33 and bushing 29 are retained on the roller by a disk 36 engaging the end of the housing and secured to the closed end 37 of the roller by a machine screw 38 extending through the washer and threaded into a threaded opening 39 in the closed end of the roller.

Thus it is apparent that the roller is free to rotate within the bushing 29, and when the port 31 aligns with the port 30 a vacuum is drawn through the roller and as soon as the port 31 moves out of alignment with the port 30, the vacuum is cut off from the roller.

Mounted in the opposite end of the roller 7 is a tubular plug member 40 adapted to be slid snugly into the end of the roller to close certain of the openings 28 not covered by the stack of blanks. The plug member 38 is fixed in adjusted position by a set screw 41 extending through a threaded opening 42 in the hub of the gear 11 and through an opening 43 in the roller to bear against the plug member. The plug member is also provided on its outer end with a handle 44 to aid in its adjustment.

Formed in the indrawing roller 7 on the side opposite to the openings 28 is a reduced portion 45 extending substantially half the circumference and length thereof so that when the reduced portion comes into alignment with the forming roller the surfaces thereof are out of contact with each other and a space is formed therebetween to allow the blank free movement between the rollers as later described.

In operating a feeding apparatus constructed and assembled as described, a stack of blanks is positioned on the plate 3 and supported by the posts 6. The lug member 40 is then adjusted to close certain of the openings 28 not covered by the blanks. The machine will then be started to operate the feeding rollers and as soon as the first line of openings 28 comes into alignment with the lowermost blank in the stack, the ports 30 and 31 will have registered to produce a vacuum through the openings 28 to draw the blank downwardly into contact with the periphery of the roller. Attention is directed to the fact that the concaved edge 9 of the plate covers the rows of openings until they are in position to move into contact with the blank, thereby preventing the blank from being drawn by suction between the edge of the plate and the roller. As the successive rows of openings move into position from under the plate, the vacuum drawn through

said rows aids in additionally gripping the blank to the roller.

Continued rotation of the roller will cause the blank to cup between it and the forming roller so that the blank is engaged therebetween and creased thereby during its feed therethrough into engagement with the forwarding rollers 24 and 25. At the time the crease formed in the blank is about to be engaged with the forwarding rollers, the reduced portion 45 will come into position to free the blank from engagement with the counter roller to allow the forwarding rollers to pull the blank therefrom without resistance, due to pressure of the forming roller. At this point the ports 30 and 31 have moved from alignment to shut off the vacuum.

What we claim and desire to secure by Letters Patent is:

1. Apparatus of the character described including a support for a stack of blanks and having a delivery opening, a pair of rollers rotatably positioned in the opening, means associated with one of the rollers for creating vacuum to cause the lowermost blank in the stack to engage the roller, and means for rotating the rollers to draw the blank from the stack, one of said rollers having a reduced portion to free the blank from frictional engagement with the rollers during a portion of their rotation.

2. Apparatus of the character described including a support for a stack of blanks, a pair of rotatably mounted rollers associated with the support for removing blanks from the stack, means for inducing vacuum in one of the rollers to cause engagement of a blank with the roller, and means for operating the rollers to draw the blanks from the stack, one of said rollers having a reduced segmental portion to free the blanks from driving engagement with the rollers during part of their movement.

3. Apparatus of the character described including a plate for supporting a stack of blanks, a tubular indrawing roller having a plurality of apertures extending through the wall thereof, a line for inducing vacuum in the interior of the roller to draw a blank to the roller, a valve for controlling communication between the vacuum line and the roller, means for actuating the roller to withdraw a blank from the bottom of the stack, and a counter roller associated with the indrawing roller, one of said rollers having a reduced segmental portion to free the blank during part of their rotation.

4. Apparatus of the character described including a plate for supporting a stack of blanks, a tubular indrawing roller having a segmental portion provided with a plurality of apertures extending through its wall and having a reduced segmental portion, a vacuum line in communication with the interior of the roller, a valve for controlling communication

cation between the vacuum line and the interior of the roller, a counter roller in yielding contact with the indrawing roller, and means for actuating the rollers to withdraw a blank and fold it between the rollers.

5. In apparatus of the character described including means for supporting a stack of blanks, a pair of rollers associated with the supporting means and having peripheral contact through a portion of their rotation for folding a blank, vacuum means associated with one of the rollers for drawing the blank into contact with one of the rollers, means for actuating the rollers, and means for drawing the folded blank from the rollers at the time the peripheries of said rollers are out of contact.

10. In apparatus of the character described including a plate for supporting a stack of blanks, a tubular indrawing roller having a plurality of apertures extending through a segmental portion of the wall of the roller and having a reduced segmental portion, a vacuum line in communication with the interior of the roller, a valve actuated by the roller for controlling communication between the vacuum line and the interior of the roller, means associated with the indrawing roller to fold the blank and means for actuating the 15 roller to withdraw a blank from the bottom of the stack.

15. In apparatus of the character described including a plate for supporting a stack of blanks, a tubular indrawing roller having a plurality of apertures extending through the wall of the roller, a vacuum line in communication with the interior of the roller, means for rendering certain of the apertures ineffective, a valve actuated by the roller for controlling communication between the 20 vacuum line and the interior of the roller, and means for actuating the roller to withdraw a blank from the bottom of the stack.

25. In apparatus of the character described, a support for a stack of blanks, a pair of rotary members associated with the support and effective to draw a blank therebetween during part of their rotation, a vacuum line communicating with one of the members to cause a vacuum to draw a blank into engagement with said member to carry it between the members to effect an initial fold, and means adjacent said members to engage the fold of the blank during the ineffective part 30 of their rotation for withdrawing the blank from between said members.

35. In apparatus of the character described, a support for a stack of blanks, a pair of rotary members associated with the support and effective to draw a blank therebetween during part of their rotation, a vacuum line communicating with one of the members to cause a vacuum to draw a blank into engagement with said member to carry it between the members to effect an initial fold, means

adjacent said members to engage the fold of the blank during the ineffective part of their rotation for withdrawing the blank from between said members, and valve means timed with the rotary members to shut off the vacuum when the blank is about to be engaged by said engaging means.

40. In apparatus of the character described including a support for a stack of blanks, a hollow rotary indrawing member having a segmental portion provided with a plurality of apertures arranged longitudinally of the segmental portion, a vacuum line in communication with the rotary member to effect a vacuum through said apertures to draw a blank into contact with the rotary member, means for rendering certain of the apertures ineffective, a valve operable in timed relation with said rotary member to control the vacuum, and means for actuating said rotary member.

45. In apparatus of the character described, a support for a stack of blanks, a hollow rotary member having a segmental portion provided with a plurality of rows of apertures, means associated with the support for covering said apertures until they come into position with the stack, a vacuum line communicating with said rotary member to draw a vacuum through the apertures for drawing a blank into contact with the roller, a counter rotary member associated with the hollow rotary member to crease the blank therebetween, and means for shutting off the vacuum after the crease is formed.

50. In apparatus of the character described, a support for a stack of blanks, a hollow rotary member having a segmental portion provided with a plurality of rows of apertures, means associated with the support for covering said apertures until they come into position with a stack, a vacuum line communicating with said rotary member to draw a vacuum through the apertures for drawing a blank into contact with the roller, a counter rotary member associated with the hollow rotary member to crease the blank therebetween, means for shutting off the vacuum after the crease is formed, and forwarding rollers for engaging the blank to withdraw it from between said rotary members.

55. In apparatus of the character described, a support for a stack of blanks, a hollow rotary member having a segmental portion provided with a plurality of rows of apertures, means associated with the support for covering said apertures until they come into position with the stack, a vacuum line communicating with said rotary member to draw a vacuum through the apertures for drawing a blank into contact with the roller, a counter rotary member associated with the hollow rotary member and effective therewith during part of the rotation of said members to crease the blank, means for shutting off the

off the vacuum after the crease is formed and forwarding rollers for engaging the blank to withdraw it from between said rotary members during the ineffective part of the rotation.

14. In apparatus of the character described including a plate for supporting a stack of blanks and having a delivery opening provided with a concave edge, a hollow indrawing roller having a plurality of apertures extending through the wall thereof and positioned in the delivery opening so that the concaved edge of the opening is adapted to cover said apertures, means for inducing a vacuum in the roller to cause engagement of a blank with the roller, a counter roller co-operating with the indrawing roller to fold the blank, and means for operating the rollers.

20. In testimony whereof we affix our signatures.
